[57] CLAIM

The ornamental design for a self-massager, as shown and described.

DESCRIPTION

FIG. 1 is a front perspective view of a self-massager embodying my new design thereof;

FIG. 2 is a front elevational view of the self-massager shown in FIG. 1, the rear elevational view being a mirror image thereof;

FIG. 3 is a right side elevational view of the self-massager shown in FIG. 1, the left side elevational view being a mirror image thereof;

FIG. 4 is a top plan view of the self-massager shown in FIG. 1;

FIG. 5 is a bottom plan view of the self-massager shown in FIG. 1; and,

FIG. 6 is another front perspective view of the self-massager shown in FIG. 1, but depicted with the arms thereof in a retracted state.

FIG. 1

*FIG. 3**FIG. 2*FIG. 4

FIG. 5

FIG. 6
